UNITED STATES PATENT OFFICE.

NATHANIEL V. HAUGHTON, OF ALAMEDA, CALIFORNIA.

EXCAVATING-MACHINE.

1,320,328.

Specification of Letters Patent. Patented Oct. 28, 1919.

Application filed January 16, 1918. Serial No. 212,022.

To all whom it may concern:

Be it known that I, NATHANIEL V. HAUGHTON, citizen of the United States, residing at Alameda, in the county of Alameda and

5 State of California, have invented certain new and useful Improvements in Excavating-Machines, of which the following is a specification.

This invention is an improved excavating 10 machine particularly useful for road grading and irrigation ditch digging.

In this specification and the annexed drawings, I disclose my invention in the form which I consider the best, but I do not limit 15 my invention to such form because it may be embodied in other forms and it is to be understood that in and by the claims following the description herein I intend to cover my invention in whatever form it may 20 be embodied.

Referring to the drawings:

Figure 1 is a side elevation of my invention.

Fig. 2 is a plan view thereof.

25 Fig. 3 is a sectional view taken on line 3-3 of Fig. 2.

Fig. 4 is a transverse sectional view taken on line 4-4 of Fig. 1.

30 Fig. 5 is a fragmentary cross section of the excavator on line 5 of Fig. 1 illustrating the elevator mounting means.

Fig. 6 is a cross section of the excavator also on line 5 of Fig. 1 illustrating the scarifier mounting means.

35 In the drawing, 1 indicates a truck including a body 2, rear wheels 3 and front wheels 4, the axle 5 of said front wheels being pivoted by king bolt 6 to the front end of said body. Draft means 7 are connected 40 to the front axle 5 by couplings 8. The body 2 is provided with a slot 9 which receives a rectangular scoop and elevator frame 10 which frame is pivoted at its forward end to the body 2 by pivots 11. The rear end member 12 is pivoted at its ends by pins 13 to the side members of the frame 10 so that it may rock.

45 A screw 14 extends downwardly through the rear frame member 12 and is connected 50 by ball and socket joint 15 to cross beam 16 of the truck body. The frame member 12 is provided with a slot 17 which receives a nut 18 which engages the screw 14. A hand wheel 19 is secured to the upper end of the screw 14. A scoop or shovel 20 is secured

at the upper part of its rear wall 21 to the member 12 of the scoop and elevator frame 10. An elevator 25 is provided for elevating the dirt from the scoop 20. Said elevator includes a frame 26, lower and upper 60 sprockets 27 and 28 journaled respectively in the lower and upper ends of said frame, chains 29 traveling over and engaging said sprockets, and buckets 30 secured to said chains. The elevator is pivotally mounted 65 on the scoop and elevator frame 10 by shaft 31 and bearings 32 and 33 through which said shaft extends, said bearings being respectively secured to the frame 10 and the elevator frame 26. Collars 35 surround the 70 shaft 31 adjacent the bearings 33 and set screws 36 in said collars engage the shaft 31 and hold the collars rigid on said shaft so as to engage the bearings 33 and hold the shaft 31 in its bearings. Braces 40 connect 75 the elevator frame 26 and the side members of the scoop and elevator frame 10 and hold the elevator in a forwardly inclined position. The brace rods are made in two sections, threaded at their adjacent ends and engaged by turnbuckles 41, whereby the rods may be extended and shortened and the inclination of the elevator adjusted. The lower end of the elevator extends into the scoop 20 so that its buckets 30 take up the 80 dirt completely from the scoop. The lower sprockets 27 are secured to shaft 42 journaled in the lower end of the elevator frame 26. The upper sprockets 28 are secured to a shaft 43 journaled in the upper 85 end of the elevator frame 26. A shaft 45 extending transversely of the truck frame and scoop and elevator frame 10 is journaled in bearings 46 on the truck frame 2 at the sides thereof, on which shaft is secured sprocket 47 and pulley 48. A chain 49 extends over sprocket 47 and over a sprocket 51 on the elevator sprocket shaft 43. An engine, preferably a gas engine 55 is mounted on the rear of the truck frame 2, on the 90 drive shaft of which is secured a pulley 56. A belt 57 passes over the pulleys 56 and 48. A conveyer 60 is mounted on a turntable 61 on the front part of the truck frame 2. Said conveyer includes a frame 62, a drive pulley 105 63 journaled in the lower end of said frame, an idler pulley 64 journaled in the upper end of said frame and a conveyer belt 65 passing over said pulleys. The lower end of the conveyer frame 62 is pivotally mounted in the 110

upper end of turntable bracket 61^a on pivot 64. Braces 65 (Fig. 4) are connected at their extremities to the turntable 61 and to the upper portion of the conveyer frame 62 which hold the conveyer in an upwardly and forwardly inclined position. Said braces are made in two sections threaded on their adjacent ends and engaged by turnbuckle 66 by means of which said braces may be extended and shortened and the inclination of the conveyer 60 adjusted. A shaft 70 extending transversely under the forward part of the truck frame 2 is journaled in bearings 71 depending from the truck frame 2. A worm 72 is secured on the shaft 70 which meshes with a worm gear 73 secured on the lower end of vertical shaft 74 journaled in turntable bearing 75 coaxial with the turntable 61, and on the upper end of said shaft is secured a beveled gear 76 in mesh with a beveled pinion 77 on shaft 78 extending diametrically of the turntable and journaled in bearings in the turntable bracket 61^a. The conveyer pulley 63 is secured on a shaft 79 suitably journaled in the lower end of the conveyer frame 62. Sprockets 80 and 81 are respectively secured on the outer ends of shafts 78 and 79 and a chain 82 travels over said sprockets. Sprockets 85 and 86 are respectively secured on the outer ends of shafts 70 and 45 and a chain 87 passes over said sprockets. A dirt breaking element which may be in the form of a scarifier 90 is provided in front of the scoop 20 for breaking up the dirt to be scooped up by the scoop. The scarifier is mounted on the frame 2 by means of scarifier frame 91 and bearings 92 on the frame 2 in which bearings the upper arm members of the scarifier frame 91 are mounted to move upwardly and downwardly to raise and lower the scarifier. On the upper arm members of the scarifier frame 91 are racks 93 engaged by pinions 94 on shaft 95 extending transversely under the truck frame 2 and journaled in bearings 96 depending from the truck frame. A worm gear 97 on the shaft 95 meshes with a worm 98 on shaft 99 journaled in bearings 100 and 101 on the truck frame 2. Collars 102 and 103 are secured to the shaft 99 adjacent the respective ends of the bearing 101 to hold the shaft 99 journaled in proper position and the worm 98 in engagement with worm gear 93. A hand wheel 105 is secured on the rear end of shaft 99 for turning said shaft and raising and lowering the scarifier through the medium of worm 98, worm gears 94 and racks 93.

The elevator 25 is driven by the engine 55 through the medium of pulley 56, belt 57, pulley 48, sprocket 47, chain 49 and pulley 51 to operate the elevator 25 to elevate the dirt from the scoop 20 and deliver the dirt onto the lower end of the conveyer.

The conveyer 60 is driven by the engine 55 through the medium of the elevator driving means and the sprocket 86, chain 87, sprocket 85, worm 72, worm gear 73, beveled gear 76, beveled pinion 77, sprocket 80, 70 chain 81 and sprocket 82.

The conveyer 60 may be turned on its turntable into position so that it will deliver the dirt to either side of the excavator or to the front thereof.

Having described my invention, I claim as new and desire to secure by Letters Patent:

1. An excavating machine comprising a draft frame, traction wheels for the frame, a second frame pivoted at one end to said draft frame and having a scoop depending from the opposite end portion thereof, means supporting and for adjusting the said opposite end of the second frame relatively to the draft frame, a third frame pivoted at an intermediate portion thereof in the second frame and having one end projecting into said scoop, an endless elevator means traveling over said third frame, and means on the draft frame for receiving material from the other end of said third frame.

2. An excavating machine comprising a draft frame, traction wheels for the frame, a second frame pivoted on said draft frame and having a scoop depending therefrom, means for adjusting said second frame relatively to the draft frame, a third frame adjustably mounted on the second frame and having one end projecting into the scoop, 100 an endless elevator means traveling over said third frame, means for adjusting the third frame relatively to the draft frame independently of the adjustment of said second frame, and means on the draft frame for receiving material from the elevator means.

3. An excavating machine comprising a draft frame, a second frame vertically adjustable on the draft frame and having a scoop depending therefrom, a third frame 110 adjustably mounted on the second frame and movable to varying inclined positions, and an endless elevator means traveling over said third frame and having one end associated with the scoop to receive material therefrom, 115 the adjustability of the third frame being independent of the adjustment of the second frame.

4. In an excavating machine and in combination a draft frame, a scoop depending from a rear portion of the frame, a toothed earth breaking element depending from the frame and in advance of said scoop, a conveying means pivoted on the front end of the frame to swing from side to side of the latter, another frame mounted on the draft frame and movable to varying inclined positions, an endless elevator means traveling over said other frame and having one end associated with the scoop to receive material 130

therefrom while its other end is associated with the conveying means to deposit the material on the latter.

5. In an excavating machine and in combination, a draft frame, a scoop depending from a rear portion of the frame, means for vertically adjusting the scoop relatively to the draft frame, a toothed earth breaking implement depending from the frame and 10 in advance of the scoop, means for independently vertically adjusting said earth breaking implement relatively to the frame, a conveyer pivotally mounted on the front portion of the frame and adapted to swing
- from side to side of the latter, another frame 15 mounted on the draft frame and movable to varying inclined positions independently of the adjustments of the scoop and the toothed implement, an endless elevator traveling over said other frame and having one end 20 associated with the scoop to receive material therefrom while its other end is associated with the conveyer to deposit the material on the latter, and power means on the draft frame having operative connection 25 for actuating said elevator and conveyer.

In testimony whereof I affix my signature.

NATHANIEL V. HAUGHTON.
